UNITED STATES PATENT OFFICE.

GEORGE J. DUFFETT, OF ST. LOUIS, MISSOURI, ASSIGNOR TO SIMMONS HARD-
WARE COMPANY, OF ST. LOUIS, MISSOURI, A CORPORATION.

COAL-HOD.

No. 844,856.

Specification of Letters Patent.

Patented Feb. 19, 1907.

Application filed August 15, 1906. Serial No. 330,691.

To all whom it may concern:

Be it known that I, GEORGE J. DUFFETT, a citizen of the United States, residing in the city of St. Louis, in the State of Missouri, have invented certain new and useful Improvements in Coal-Hods, of which the following is a full, clear, and exact description, reference being had to the accompanying drawings, forming part of this specification.

My invention relates to a coal-hod provided with a double bottom for the purpose of affording a greater degree of strength in the bottom, which is the part of the hod that is subjected to the greatest amount of strain and is therefore most readily susceptible of injury.

Figure I is a view, partly in elevation and partly in vertical section, of my coal-hod. Fig. II is an enlarged vertical section of the lower portion of the hod with the parts in assembled condition. Fig. III is an enlarged vertical section of the lower portion of the coal-hod with the parts in separated condition.

A designates the body of the hod, which is formed of sheet metal, as usual, and is provided at its lower end with an inturned flange *a*.

B designates the main bottom of the hod. This main bottom consists of a rim 1 and an upper bottom sheet 2. At the junction of said rim and upper bottom sheet is a return-bend 3, that is separated from the upper horizontal portion 1' of the bottom rim to provide a continuous space 4, which is adapted to receive the inturned flange *a* of the hod-body. Within the return-bend 3 is a space 5.

6 is a supplemental bottom sheet that is adapted to be introduced into the main bottom immediately beneath the main bottom sheet 2 and the edge of which occupies the space 5 within the return-bend 3. In the manufacture of the hod the supplemental bottom is placed in the position stated, and the inturned body-flange *a* is introduced into the space 1', after which the return-bend 3 is firmly clamped to confine both the inturned flange of the hod-body, whereby the parts are firmly bound together and all liability of a displacement is prevented.

A hod constructed in the manner described

embodies the essential characteristics of strength and rigidity with a minimum increase of cost and labor as compared to similar hods in which but a single bottom is present and which are extremely liable to become damaged in placing such heavy material as coal therein.

In one of the bottom sheets of my hod I perform one or more perforations. These perforations are preferably produced in the supplemental bottom sheet, as indicated at 7. The purpose of providing such perforation or perforations is to prevent bulging of the bottom sheets, due to the expansion of air present between the sheets when the hod is subjected to a galvanizing-bath for the purpose of giving it a preservative coating. As is well known, galvanizing-baths are always maintained in a heated condition when articles to be galvanized are dipped thereinto, and it is obvious that where two parts of an article are held in closely-assembled condition when the article is dipped into the galvanizing-bath the air that is present between 75 said parts will be expanded, due to the presence of heat, and cause one or both of the parts to be bulged outwardly. This bulging action would naturally be detrimental to the bottom sheets of my coal-hod; but by the 80 provision of the perforation or perforations in one of the bottom sheets I completely overcome the objectionable action referred to, due to the air which would otherwise be confined between the bottom sheets finding 85 ready vent when the coal-hod is dipped into a galvanizing-bath.

I claim—

A coal-hod comprising a body having an inturned flange at its lower end, a main bottom part comprising a rim and an upper bottom sheet with a return-bend at the junction of said members providing a space above said rim for the reception of said inturned body-flange, and a supplemental bottom sheet located beneath and lying flatly against said upper bottom sheet and seated within said return-bend, substantially as set forth.

GEO. J. DUFFETT.

In presence of —

JAMES J. KEOUGH,
E. HACKEMYER.
